UNITED STATES PATENT OFFICE

DANIEL ADAMS, OF TOLEDO, OHIO, ASSIGNOR TO LIBBEY-OWENS-FORD GLASS COMPANY, OF TOLEDO, OHIO, A CORPORATION OF OHIO

PROCESS AND APPARATUS FOR PRODUCING SHEET GLASS

Application filed September 7, 1929. Serial No. 391,019.

The present invention relates to an improved process and apparatus for producing sheet glass.

An important object of the invention resides in the provision of a process and apparatus for forming and annealing sheet glass wherein the glass sheet is adapted to be formed at a relatively high rate of speed and deposited, as it is formed, upon a conveying means traveling at substantially the same speed, the sheet being subsequently transferred from the conveying means into a leer and annealed while traveling through said leer at a speed relatively less than the speed at which it was formed.

Another object of the invention is the provision of such a process and apparatus wherein a mass of molten glass is reduced to sheet form and the sheet deposited as it is formed upon suitable conveying mechanism, said sheet being subsequently shifted transversely of its line of formation to transfer the same from said conveying mechanism into an annealing leer.

Another object of the invention is the provision of conveying mechanism of a novel and improved construction having means associated therewith adapted to raise or lift the sheet therefrom when the conveying mechanism is in a position opposite the annealing leer to facilitate the transfer of the sheet from said conveying mechanism into said leer.

Other objects and advantages of the invention will become more apparent during the course of the following description when taken in connection with the accompanying drawings.

In the drawings forming a part of this application and wherein like numerals are employed to designate like parts throughout the same,

Fig. 1 is a plan view of apparatus provided by the present invention, partially broken away to illustrate certain parts thereof more clearly,

Fig. 2 is a section taken substantially on line 2-2 of Fig. 1, and

Fig. 3 is a section taken substantially on line 3-3 of Fig. 1.

In the formation of the glass sheet, a mass

of molten glass 10 is adapted to be initially deposited upon a receiver or support 11 from a pot or other receptacle 12, and subsequently moved therefrom between a pair of forming rolls 13 and 14 which serve to reduce the glass to a sheet 15 of substantially predetermined and uniform thickness. The molten glass 10 is preferably deposited upon the receiver 11 while said receiver is in a substantially horizontal position as indicated by the broken lines in Fig. 2, after which the receiver is tilted upwardly as shown by the full lines to cause the molten glass to pass downwardly between the forming rolls 13 and 14. The forming rolls 13 and 14 are associated with one end of the receiver 11 and are spaced from one another to create a sheet forming pass therebetween, the width of which determines the thickness of sheet produced. One of the forming rolls is adapted to be positively driven such as through a chain drive 16 (Fig. 1) and the other roll is driven from the positively driven roll through the intermeshing gears 17 carried by the shafts 18 of the forming rolls which are rotatably supported in the bearing brackets or standards 19 and 20. The glass sheet 15 passes downwardly from the forming rolls over an inclined runway or apron 21 and is laid upon one or a plurality of tables 22 movable therebeneath.

The table 22 comprises a preferably metallic body portion or sub-structure 23 supported upon wheels 24 which run along a trackway 25. The body portion 23 of the table is provided with a plurality of spaced transversely extending slots 26. Supported or built up upon the bottom 23 is the refractory super-structure 27 upon which the glass sheet 15 is adapted to rest, said super-structure being also provided with slots 28 in registry with the slots 26 in body portion 23. Carried by the under side of the table is a plate 29 which extends throughout substantially the entire length and width thereof to form a chamber 30 beneath the table and which is in communication with all of the slots 26 and 28. Associated with the plate 29 are the two connections 31 and 32 to which are adapted to be removably secured the flexible conduits 33 and 34 when the table is in position oppo-

site the intake end of the annealing leер. The flexible conduits 33 and 34 are connected to a blower 34' for a purpose to be more clearly hereinafter set forth.

5 Arranged in advance of the sheet forming mechanism is a heating kiln or preheating chamber 35, the temperature of which may be controlled by a plurality of burners 36 or in any other suitable manner. The trackway 10 25 is adapted to extend through the heating kiln 35 so that the tables 22 are first passed to the right through the kiln so that they may be preheated to the desired temperature before receiving the glass sheet thereupon. By 15 preheating the tables in this manner, the glass will not be unduly chilled as it comes into contact therewith. The table may be propelled along the trackway 25 by means of one or a plurality of drive pinions 37 meshing with rack bars 38 secured to the undersides thereof.

The length of the conveyor table 22 is preferably such that it will support at one time the entire sheet 15 formed from the mass of 25 molten glass 10. During the formation of the sheet the table 22 is moved to the right beneath the runway 21 so that the sheet will be laid upon the table. The mass of molten glass 10 is adapted to be rapidly reduced to sheet 30 form and this may be accomplished by driving the forming rolls 13 and 14 at a relatively high rate of speed. During the formation of the sheet, the linear speed of the table 22 is of course adapted to be substantially the same as 35 the peripheral speed of the forming rolls so that as the sheet is laid upon the table it will not be buckled, warped or otherwise distorted.

The trackway 25 is arranged to convey the 40 table 22 to a position opposite the intake end of an annealing leер 39 which extends at substantially right angles to the line of formation of the sheet and which is provided at one end with a slot 40 for receiving the sheet 45 therein and at its opposite end with a slot 41 through which the sheet passes therefrom. When the table is brought into position opposite the intake end of the leер as indicated by the broken lines in Fig. 1, the sheet is pushed 50 laterally or transversely from said table into said leер. In other words, the sheet is carried forwardly from its point of formation until it is in a position opposite the leер and is then shifted transversely thereinto.

55 The sheet 15 is supported and carried through the leер 39 upon an endless conveyor 42, said conveyor extending outwardly beyond the leер at opposite ends thereof and being composed of a plurality of idler rollers 60 43 mounted upon shafts 44 which are secured at their opposite ends to the endless chains 45 and 46 which consist of a plurality of intermeshing and overlapping links pivotally associated with one another. The endless 65 conveyor 44 is trained about drums 47 and 48

mounted upon shafts 49 journaled at their opposite ends in bearings 50 and 51. The drums 70 47 and 48 carry sprockets 52 and 53 respectively, which are adapted to engage the chains 45 and 46 to effect the desired movement thereof. The drums are located outwardly of the opposite ends of the leер as shown and one of said drums is positively driven from a suitable drive means 54. The upper horizontal flight of the conveyor is supported upon a plurality of spaced longitudinally extending rails 55, extending throughout the leер 39. These rails are adapted to support the rollers 43 during the horizontal run of the conveyor and also serve to effect rotation thereof. In other words, as the endless conveyor 75 42 is driven to carry the sheet resting thereupon through the annealing leер, the rollers 43 will also be independently rotated upon the shafts 44 due to their rolling engagement 80 with the rails 55.

After the table 22 has been moved beneath the forming rolls 13 and 14 to receive the sheet therefrom and the said table and sheet then brought to a position opposite the intake end of the leер, the movement of the table is stopped and the sheet then shifted transversely into the leер wherein it is supported and carried along upon the endless conveyor 42. In order to facilitate the shifting of the sheet from the table into the leер, the flexible conduits 33 and 34 are secured to the table connections 31 and 32. The blower 34' is then operated to force a blast of preferably hot air through the conduits 33 and 34 into the chamber 30 from which it will pass upwardly through the slots 26 and 28 and impinge against the bottom of the glass sheet resting upon the table. The force or pressure of this hot air blast upon the under side of the sheet will tend to lift or raise the sheet slightly from off the table and thus facilitate the sliding or pushing thereof transversely from the table into the leер. In other words, the hot air blast will tend to loosen or lift the sheet and thereby reduce the frictional resistance between the sheet and table so that the sheet can be pushed from the table into the leер in an easy and convenient manner and without injury thereto.

While only a single relatively long endless conveyor 42 has been disclosed for carrying the glass sheets through the annealing leер 39, it will be apparent that a plurality of relatively short conveyors may be arranged end to end within the leер. The rails 55 are preferably disposed at an angle as shown in Fig. 1 so that the rollers 43 will not be grooved thereby as they are caused to travel thereover.

It is to be understood that the form of the invention herewith shown and described is to be taken as the preferred embodiment of the same, and that various changes in the

shape, size and arrangement of parts may be resorted to without departing from the spirit of the invention or the scope of the subjoined claims.

5 I claim:

1. The process of producing sheet glass, consisting in first forming the sheet, resting the newly formed sheet upon a supporting surface, decreasing the frictional resistance between the sheet and surface, and in then sliding the sheet from said surface into an annealing chamber.

10 2. The process of producing sheet glass, consisting in first forming the sheet, resting the newly formed sheet upon a supporting surface, creating a pressure beneath the sheet tending to lift the same from said surface, and in then sliding the sheet from the surface into an annealing chamber.

15 3. The process of producing sheet glass, consisting in first forming the sheet, resting the newly formed sheet upon a supporting surface, lessening the frictional resistance between the sheet and surface by directing an air blast upon the under side thereof, and in then sliding the sheet from said surface into an annealing chamber.

20 4. The process of producing sheet glass, consisting in first forming the sheet, resting the newly formed sheet upon a supporting surface, creating an air blast beneath the sheet tending to lift the same from said surface, and in then sliding the sheet from the surface into an annealing chamber.

25 5. The process of producing sheet glass, consisting in reducing a mass of molten glass to sheet form, depositing the sheet as it is formed upon a movable surface, conveying the sheet forwardly upon said surface to a position adjacent an annealing chamber, in decreasing the frictional resistance between the sheet and surface, and in then sliding the sheet from said surface into the annealing chamber.

30 6. The process of producing sheet glass, consisting in reducing a mass of molten glass to sheet form, depositing the sheet as it is formed upon a movable surface, conveying the sheet forwardly upon said surface to a position adjacent an annealing chamber, lessening the frictional resistance between the sheet and surface by directing an air blast upon the under side thereof, and in then sliding the sheet from said surface into the annealing chamber.

35 7. The process of producing sheet glass, consisting in reducing a mass of molten glass to sheet form, depositing the sheet as it is formed upon a movable surface, conveying the sheet forwardly upon said surface to a position adjacent an annealing chamber, creating an air pressure beneath the sheet tending to lift the same from the supporting surface, and in then sliding the sheet from said surface into the annealing chamber.

8. In sheet glass apparatus, a movable table for supporting a newly formed sheet thereupon and for conveying it to a desired location, said table having a plurality of openings in the top thereof and a chamber 70 communicating with said openings.

9. In sheet glass apparatus, a movable table for supporting a newly formed sheet thereupon and for conveying it to a desired location, said table having a plurality of openings in the top thereof and a chamber 75 communicating with said openings, and means for creating an air blast within said chamber.

10. In sheet glass apparatus, a movable 80 table having a refractory portion for supporting a newly formed sheet thereupon and being adapted to convey said sheet to a desired location, said refractory portion having a series of openings therein.

11. In sheet glass apparatus, a movable 85 table having a refractory portion for supporting a newly formed sheet thereupon and being adapted to convey said sheet to a desired location, said refractory portion having 90 a series of openings therein and a chamber communicating with said openings.

12. In sheet glass apparatus, a movable 95 table having a refractory portion for supporting a newly formed sheet thereupon and being adapted to convey said sheet to a desired location, said refractory portion having a series of openings therein and a chamber communicating with said openings, and means for creating an air blast within said 100 chamber.

13. In apparatus for producing sheet glass, means for reducing a mass of molten glass to sheet form, a movable table for receiving the sheet as it is formed thereupon and for conveying it to a desired location, an annealing leer for receiving the sheet from the table, and means for decreasing the frictional resistance between the sheet and table to facilitate the transfer of said sheet into 105 said leer.

14. In apparatus for producing sheet glass, means for reducing a mass of molten glass of sheet form, a movable table for receiving the sheet as it is formed thereupon and for conveying it to a desired location, an annealing leer for receiving the sheet from the table, and means for creating a pressure upon the under side of the sheet tending to lift the same from the table to facilitate its transfer into said leer.

15. In apparatus for producing sheet glass, means for reducing a mass of molten glass to sheet form, a movable table for receiving the sheet as it is formed thereupon and for conveying it to a desired location, said table having a plurality of openings in the top thereof and a chamber communicating with the openings, an annealing leer for receiving the sheet from the table, and means for 115 120 125 130

creating an air blast within said chamber tending to lift the sheet from the table to facilitate the transfer of said sheet into said leer.

5 Signed at Toledo, in the county of Lucas and State of Ohio, this 16th day of August, 1929.
